UNITED STATES PATENT OFFICE

FRANK A. HALLECK, OF MICHIGAN CITY, INDIANA, ASSIGNOR TO SULLIVAN MACHINERY COMPANY, A CORPORATION OF MASSACHUSETTS

TRACTOR

Original application filed April 10, 1924, Serial No. 705,691. Divided and this application filed January 11, 1927. Serial No. 160,487.

This invention relates to loading machines and more particularly to improved feeding mechanisms for such machines.

This invention has for its main object to provide an improved feeding mechanism for a coal loading machine especially adapted for use in coal mines. Another object of this invention is to provide an improved loading machine supported on endless tracklaying treads and having improved mechanism for driving and controlling movement of the treads whereby the machine may be fed in an improved and more flexible manner. Yet another object of this invention is to provide improved plural speed transmission means between the motor and the tracklaying treads. A more specific object of my invention is to provide, in a plural speed transmission, mechanism whereby a fast forward and fast reverse speed can be obtained and a slow forward speed obtained by the simultaneous operation of the fast reverse and fast forward feed transmission means. These and other objects and advantages of this invention will, however, subsequently more fully appear.

In the accompanying drawings there is shown for purposes of illustration one form which the invention may assume in practice.

In these drawings,—

Fig. 1 is a side elevation of the improved loading machine, the view being partially broken away in section to illustrate details of the improved feeding mechanism.

Fig. 2 is a longitudinally extending vertical sectional view taken substantially on line 2—2 of Fig. 6.

Fig. 3 is a detail sectional view taken on line 3—3 of Fig. 7.

Figs. 4 and 5 are detail views of the controlling mechanism for the feed controlling clutches.

Fig. 6 is a transverse vertical sectional view taken on line 6—6 of Fig. 1.

Fig. 7 is a horizontal sectional view taken substantially on line 7—7 of Fig. 1.

Fig. 8 is a detail sectional view taken substantially on line 8—8 of Fig. 7 and illustrating operating means for the control frictions.

Fig. 9 is a detail sectional view taken substantially on line 9—9 of Fig. 7 and illustrating the brakes and operating means therefor.

In this illustrative form of the invention, which is a division of my copending application Ser. No. 705,691, filed April 10, 1924, there is shown a loading machine especially adapted for loading loose coal or other similar material; and this machine generally comprises a machine frame 1 supported on endless tracklaying treads 2, the frame 1 being pivotally mounted at the rear end thereof on the tread structure about a horizontally transversely extending axis at 3, while the forward end of this frame is supported on the tread structure by means of a transversely extending cross bar or rocker arm 4. The rocker arm 4 is pivotally connected at its ends to the tread frames 5 while the intermediate portion of this rocker arm is connected to the frame 1 in a manner clearly described in my copending application mentioned above. As is usual in traction means of the tracklaying tread type, the tread frames 5 carry bearing rollers 6 which engage the tread chains so as to support the weight of the machine thereon. The tracklaying treads 2 are adapted to be driven through improved plural speed transmission means including drive sprockets 7 arranged coaxially with the frame pivot 3 and cooperating with the tread chains. The forward ends of the tread chains are guided on a front idler wheel or roll 8 carried by the tread frames 5 and adjustably mounted thereon by usual adjusting means 9 to vary the tension of the tread chains in a well known manner. As shown in Fig. 1 the forward end of the frame 1 has supported thereon a shovel member or nose piece 10 having a transversely extending material penetrating edge, while cooperating with the shovel member is a toothed feeding roller 11 supported for swinging movement on arms 12 pivotally mounted at 13 on the machine frame 1. The toothed roller is adapted to feed the material to be loaded downwardly and rearwardly onto the shovel member 10, the material being moved rearwardly from 100

the shovel member by a front conveyor (not shown) which discharges onto a tail conveyor 14 in a manner clearly described in the above mentioned application.

5 The improved feeding mechanism as shown in the drawings specifically comprises an electric motor 15 housed within the frame 1 and having its armature shaft 16 extending longitudinally of the machine and journaled at 10 its rear end in roller bearings 17 carried within the machine frame. As shown in Fig. 1 suitably fixed to the rear end of the armature shaft 16 is a spur motor pinion 18 meshing with a spur gear 19 keyed at 20 to a shaft 21 15 extending longitudinally of the machine and journaled in suitable bearings 22 carried by the machine frame. The shaft 21 has fixed thereto at 23 a member 24, the hub of this member having fixed thereto a spur pinion 25 20 as shown in Figs. 2 and 7. The pinion 25 meshes with spur gears 26 and 27, the latter meshing with a spur gear 28, the gears 26, 27, and 28 being rotatably mounted on shafts 29, 30, and 31 respectively, the latter in turn 25 being rotatably mounted in bearings 31^a carried by the upper part of the frame 1. The gear 27 has a greater number of teeth than either of the gears 26 and 28 which have the same number of teeth, the purpose of which 30 will be hereinafter fully described. The shafts 29, 30, and 31 have arranged coaxially therewith worms 32, 33, and 34 respectively, as shown in Fig. 7. Suitable clutch mechanism is provided for connecting the gears 26, 35 27, and 28 to their respective shafts 29, 30, and 31 for rotation therewith and such means is herein shown as of the well known expanding clutch type mounted within the gears and having usual fingers or other suitable expanding mechanism 35 adapted to engage a 40 longitudinally movable cone clutch applying member 36 actuated by usual shipper mechanism 37. The shafts 29, 30, and 31 have fixed thereto brake drums 38 as shown in Figs. 3 45 and 7 with which suitable brake bands 39 cooperate.

Referring more particularly to Fig. 6 the means for driving the tracklaying treads 2 comprises separate right and left hand shafts 50 40 and 41 arranged coaxially with the pivotal axis of the machine frame 1 and the ends of these shafts have fixed thereto at 42 the driving sprockets 7 for the respective treads 2, said shafts 40 and 41 being rotatably mounted 55 within bearing sleeves 43 carried by hollow laterally projecting trunnions 44 suitably secured to the sides of the machine frame 1. The trunnions 44 are in turn rotatably mounted within bearing sleeves 45 carried 60 by the tread supporting frames 5. In accordance with this illustrative embodiment of the invention the shafts 40 and 41 have reduced inner ends 46 disposed in contiguity and rotatably mounted in bearing sleeves 47 65 carried by a centrally located bearing bracket

48 carried by the lower side of the machine frame. The shafts 40 and 41 are adapted to be driven from the motor 15 through differential mechanisms generally designated 49 and 50 respectively. The construction of 70 these differential mechanisms is somewhat similar to usual bevel gear differential mechanisms but has somewhat different connections with respect to the shafts of the driving gears than is usually had. More specifically 75 the construction of the differential 49 which is shown for illustrative purposes comprises a spider member 51 keyed to the shaft 40 and having radial stub shafts 52 upon which are rotatably mounted planetary bevel pinions 80 53. The bevel pinions 53 mesh with a bevel gear 54 rotatably mounted on the inner end of the bearing sleeve 43 and supported on the shaft 40. The bevel gear 54 is fixed by a key 56 to the hub of a worm gear 57, said 85 worm gear 57 meshing with the worm 32 so as to be driven by the latter. The planetary bevel pinions 53 also mesh with a bevel gear 58 aligned with the gear 54 and fixed to a sleeve 59 rotatably mounted in a bearing sleeve 60 90 carried by the bearing bracket 48. The sleeve 59 has fixed thereto a worm gear 61 which meshes with the worm 33 and is driven by the latter. The differential 50 is similar to the differential 49 and comprises a spider member 62 fixed to the shaft 41 and having radial stub shafts 63 on which planetary bevel pinions 64 are rotatably mounted. The bevel pinions 64 mesh with a bevel gear 65 fixed to the hub of the worm gear 61. The bevel pinions 64 also mesh with a bevel gear 66 100 rotatably mounted on the inner end of the bearing sleeve 43 and supported on the shaft 41 and this gear 66 has a hub portion fixed to the hub of a worm gear 68, the worm 34 105 meshing with the worm gear 68 so as to drive the latter.

Suitable controlling mechanism is provided for the electric motor 15 and may be of any standard type having a usual controller handle 69, while suitable control levers are provided for controlling the clutch and brake members for the shafts 29, 30 and 31. The controlling mechanism for the clutches and brakes is herein shown as comprising a forward control lever mechanism 70 having concentrically arranged inner and outer shafts 71 and 72 respectively (see Fig. 4) horizontally disposed and extending transversely of the machine, the shaft 72 being rotatably mounted in suitable bearings carried by the machine frame. The outer shaft 72 carries a bifurcated arm or yoke 73 having bearings 74 disposed on the outer end thereof and within which is rotatably mounted a shaft 75, the latter being disposed at right angles to the shafts 71 and 72. The shaft 75 has fixed thereto a bevel gear 76 meshing with a bevel gear 77 fixed to the shaft 71. Also carried by the shaft 75 is an operating control 120

lever 78 adapted when swung laterally of the machine to actuate the shaft 75 to cause partial rotation of the transverse shaft 71 and also adapted to be swung longitudinally of the machine to cause rotation of the arm 73 and consequently the outer shaft 72. Any suitable linkage connection may be used to actuate the forward feed clutches, one form of which is shown as comprising oppositely extending arms 79 and 80 fixed to the inner shaft 71 and extending through openings in the outer shaft 72. Each of the arms 79 and 80 has a loose longitudinally slidable connection with pull rods 81 and 82 respectively, the outer ends of which have enlarged abutment heads or nuts 83 adapted to engage the arms 79 and 80 upon forward movement of either. The rod 82 is fixed to a pull rod 84 also having longitudinally slidable connection with an arm 85 fixed to the outer shaft 72 and having an abutment head or nut 86. The rods 81 and 84 extend longitudinally alongside of the machine frame to the rear end thereof to operate clutch throw-out links 25 and levers 87. When the lever 78 is swung longitudinally of the machine the clutches on shafts 29 and 31 are simultaneously thrown into engagement, as both shafts 71 and 72 are simultaneously rotatable to pull the rods 81 and 84 while rod 82 will slide through the arm 80, whereas, if the lever 78 is swung transversely of the machine, only one of the clutches on shafts 29 and 31 will be thrown into engagement to cause driving of only one tracklaying tread to thereby turn the machine, for the outer shaft 72 will be held stationary while either of the arms 79, 80 will pull rods 81 or 82, depending upon whether lever 78 is thrown outwardly or inwardly to rotate the shaft 71 in opposite directions. It will be noted, however, that upon actuation of one rod the other will slide through its respective arm, leaving one clutch free. Also carried by the machine frame substantially adjacent the lever 78 is a reverse lever 88 pivotally mounted upon a horizontal shaft 89 extending transversely of the machine and suitably journaled thereon. The shaft 89 is adapted to control the clutch on the shaft 30 through suitable operating connections, a form of which is shown in Fig. 8. It is to be noted that this identical lever arrangement including the levers 78 and 88 is disposed on opposite sides of the machine as clearly shown in Fig. 6 in such manner as to enable the operator to control the machine while standing at either side thereof. The operation of the brakes 39 can of course be had through any suitable manually operable brake operating means including a cam 90 on each brake and suitable independently operable operating means, a form of which is shown in Fig. 9, for each cam.

In describing the operation of the improved feeding mechanism for the loading

machine it will first be assumed that the machine is standing still with the nose piece 10 and gathering roller 11 in position to penetrate and gather the material to be loaded, the nose piece 10 then being lowered from the position shown in Fig. 1 to the mine bottom. If it is now desired to feed the machine forwardly at a fast speed to penetrate the material the lever 78 is swung longitudinally of the machine, the brakes on shafts 29 and 31 being released, and the expanding clutches are applied connecting the worms 32 and 34 and their respective shafts 29 and 31 to the gears 26 and 28 respectively. During such operation the brake on shaft 30 is locked and the lever 88 throws the clutch controlling the shaft 30 out of engagement; thus, the worm 33 on shaft 30 is held against rotation and consequently rotation of the worm gear 61 is prevented. The worm gear 61 in turn prevents rotation of bevel gears 58 and 65. Inasmuch as the shafts 29 and 31 are now being positively driven due to the clutch engagement, worm gears 57 and 68 are driven by the worms 32 and 34 respectively, to cause rotation of the planetary bevel pinions 53 and 64 orbitally around the stationary bevel gears 58 and 65 which act as reaction gears. The stub shafts 52 and 63 of the two differential spiders will thereby be positively carried around by the pinions 53 and 64 to cause a positive rotation of the right and left hand shafts 40 and 41. If, however, it should be desired to turn the loading machine in one direction or the other one of the shafts 29 or 31 would be held stationary, while the other turns, the reverse shaft 30 also being held, thus allowing movement of only one track-laying tread or the desired fractional movement thereof. By such a construction it is possible to "zig zag" the machine as a whole bodily into the pile of material to be loaded to cause the nose piece to penetrate the same with facility. If it is now desired to impart fast reverse movement to the loading machine, shafts 29 and 31 will be held stationary by their respective brake bands while the clutches thereon are disengaged and the reverse mechanism actuated by shifting the lever 88 to throw the clutch mounted on the shaft 30 into engagement, the brake thereon being first released, to positively drive said shaft which in turn will drive the worm gear 61 in a reverse direction to drive the planetary pinions 53 and 64 in a reverse direction around the bevel gears 54 and 66 which are now held stationary by the held or stationary shafts 29 and 31. It is to be noted (see Fig. 7) that the worms 32, 33, and 34 have the same pitch but that the worms 32 and 34 on shafts 29 and 31 are right and left hand respectively. The worm gear 61 is driven in a direction opposite to that in which the worm gears 57 and 68 are driven, due to the fact that one side of the gear 25 meshes with the

gear 27, while the other side meshes with the gear 26, thus driving gears 26 and 27 in the same directions, while gear 28 will rotate in a direction opposite to the gear 26, but the worm gears driven thereby will rotate in the same direction due to the right and left hand worms 32 and 34. After the loading machine has been fed rapidly up to the pile of material to be loaded and it is desired to feed the same slowly into the material during the loading operation, all the brakes on shafts 29, 30, and 31 are released and the clutch mechanisms therefor are simultaneously thrown into engagement, connecting the worms 32, 33, and 34 and their shafts 29, 30, and 31 to the gears 26, 27 and 28 respectively for rotation therewith. This, it will be seen, simultaneously operates both the fast reverse and fast forward feed mechanisms and due to the differential action between the same a slow forward speed is obtained, the slow forward feed being obtained due to the fact that the gear 27 has a greater number of teeth than either the gear 26 or gear 28 so that the worm gear 61 has a slightly smaller angular velocity than do the worm gears 57 and 68. The smaller angular velocity of the gear 27, and consequently of the worm 33 and worm gear 61 in the reverse feed is due to the fact that the ratio of the gear 27 to the motor driving pinion 18 is greater than the ratio of the gears 26 and 28 to said motor driving pinion. The gears 27 and 25 merely act as transmission gears in the operation of the gears 26 and 28. Thus, during the slow forward movement, the worm gear 61 drives the bevel pinions 53 and 64 oppositely and at a slower speed than do the gears 57 and 68, the result being that the stub shafts 52 and 63 of the respective differential spiders will take a slow forward speed equal to the difference between the speed of the respective bevel gears meshing with the bevel pinions and this will drive the shafts 40 and 41 at a slow forward speed. It is therefore obvious that the slow forward speed is obtained by the simultaneous operation of the fast reverse and fast forward feeds. These and other operations and advantages of the improved loading machine will be clearly apparent to those skilled in this art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a loading machine comprising traction means, driving means for said traction means including a motor and means driven by said motor for feeding the machine for-

wardly and rearwardly including reverse and forward feeding mechanisms and means for effecting simultaneous operation of said forward and reverse feeding mechanisms to obtain another speed, and means for controlling said mechanisms including brake and clutch means for holding elements of both of said mechanisms stationary or for effecting rotation of said elements.

2. In a loading machine, a motor, and feeding means operated by said motor including traction members, and operating and controlling means for said traction members including coaxial rotatable elements, planet mechanism cooperating with said elements, worms operatively connected to said coaxial elements, control means for each worm including a clutch and brake, and means for effecting movement of said traction members on orbital movement of said planets.

3. In a loading machine, a motor, and feeding mechanism operated by said motor including traction members, and operating and controlling means for said traction members including coaxial elements rotating on transversely extending horizontal axes; planet mechanism cooperating with said elements, horizontal worms operatively connected to said coaxial elements, control means for each worm including a clutch and brake coaxial with each of the same, and means for effecting movement of said traction members on orbital movement of said planets.

4. In a loading machine, a motor, and feeding mechanism operated by said motor including traction members, and operating and controlling means for said traction members including coaxial rotatable elements, planet mechanism cooperating with said elements, gears operatively connected to said coaxial elements, means for rotating either of said gears while the other is held stationary, means for holding stationary either of said gears while the other is rotated, and means for effecting movement of said traction members on orbital movement of said planets.

5. In a loading machine, a motor, and feeding mechanism operated by said motor including traction members, and operating and controlling means for said traction members including coaxial rotatable elements, planet mechanism directly cooperating with said elements, independently driven gears operatively connected to said coaxial elements and respectively constituting driving elements therefor, means for separately rotating either or simultaneously rotating both of said gears including a friction clutch controlling each gear, and means for effecting movement of said traction members on orbital movement of said planets.

6. In a loading machine, feeding mechanism therefor including a plurality of pairs of coaxial rotatable elements, planet mecha-

nism cooperating with the elements of each pair, and means for rotating said coaxial elements including three gears including a central gear, the central gear driving an element of each pair, means for effecting rotation of said gears, and means for holding said central gear stationary while said other gears continue to rotate.

7. In a loading machine, feeding mechanism therefor including a plurality of pairs of coaxial rotatable elements, planet mechanism cooperating with the elements of each pair, and means for rotating said coaxial elements including three worms including a central worm, the central worm driving an element of each pair, means for effecting rotation of said worms, and means for holding said central worm stationary while said other worms continue to rotate.

20 8. In a loading machine, feeding mechanism therefor including a plurality of pairs of like coaxial rotatable elements, planet mechanism cooperating with an element of each pair, means for rotating said coaxial elements including three gears including a central gear, the central gear driving an element of each pair, means to effect rotation of said gears including means for rotating each of said gears at will or holding it against rotation while said other gears continue to rotate, and separate traction members each driven and controlled through one of said pairs of coaxial elements.

9. In a loading machine, feeding mechanism therefor including separate traction members, driving members therefor, a plurality of pairs of like coaxial rotatable elements coaxial with said driving members, planet mechanism cooperating with an element of each pair, and means for rotating said coaxial elements including three gears, the central gear driving an element of each pair and a clutch and brake controlling each gear.

45 10. In a loading machine, feeding mechanism therefor including separate traction members, driving members therefor, a plurality of pairs of like coaxial rotatable elements coaxial with said driving members, planet mechanism cooperating with an element of each pair, and means for rotating said coaxial elements including three worms, the central worm driving an element of each pair and a clutch and brake controlling each worm.

11. In a loading machine, feeding mechanism therefor including a plurality of pairs of like coaxial elements rotating on horizontal transversely extending axes, planet mechanism cooperating with an element of each pair, means for rotating said coaxial elements including three worms, the central worm driving an element of each pair, controlling means for said worms including clutches for separately or simultaneously

connecting said worms to said motor, one coaxial with each of said worms, and separate traction members each driven and controlled through one of said pairs of coaxial elements.

12. In a loading machine, feeding mechanism therefor including a plurality of pairs of like coaxial elements rotating on horizontal transversely extending axes, planet mechanism cooperating with an element of each pair, means for rotating said coaxial elements including three worms rotating on horizontal axes, the central worm driving an element of each pair, means to effect rotation of said worms including means for rotating each of said worms at will or holding it against rotation, means for controlling rotation of said worms including a driving clutch and a braking clutch coaxial with each of said worms, and separate traction members each driven and controlled through one of said pairs of coaxial elements.

13. In a loading machine, a motor, and feeding means operated by said motor including traction members, and operating and controlling means for said traction members including coaxial rotatable elements, planet mechanism cooperating with said elements and operatively connected to said traction members, worm gearing including worms operatively connected to said coaxial elements, means for holding two of said worms stationary during rotation of the third to effect driving of said traction members at one feeding speed, means for holding said third worm stationary during rotation of the first two to effect driving of said traction members at a different speed in the reverse direction, and means for effecting simultaneous rotation of said worms to drive said traction members at another feeding speed.

14. In a loading machine, a motor, and feeding means operated by said motor including traction members and operating and controlling means for said traction members including coaxial rotatable elements, planet mechanism cooperating with said elements and operatively connected to said traction members, worm gearing including worms operatively connected to said coaxial elements, means including brakes and clutches arranged coaxial with said worms for holding two of said worms stationary during rotation of the third to effect driving of said traction members at one feeding speed, and for holding said third worm stationary during rotation of said first two to effect driving of said traction members at a different speed in the reverse direction and for effecting simultaneous rotation of said worms to effect driving of said traction members at another feeding speed.

15. In a loading machine, a motor, and feeding means operated by said motor including traction members, and operating and con-

trolling means for said traction members including coaxial rotatable elements, planet mechanism cooperating with said elements and operatively connected to said traction members, worm gearing including worms operatively connected to said coaxial elements, and means including brakes and clutches coaxial with said worms for holding two of said worms stationary during rotation of the third to effect driving of said traction members at a relatively high speed in one direction, means for holding said third worm stationary during rotation of the first two to effect driving of said traction members at a relatively high speed in the reverse direction, and means for effecting simultaneous rotation of said worms to drive said traction members at a relatively slow forward feeding speed.

16. In a loading machine, a motor and feeding means operated by said motor including traction members, and operating and controlling means for said traction members including coaxial rotatable elements, planet mechanism cooperating with said elements and operatively connected to said traction members, gearing including gear elements operatively connected to said coaxial elements, means for holding two of said gear elements stationary during rotation of the third to effect driving of said traction members at one feeding speed, means for holding said third gear element stationary during rotation of the first two to effect driving of said traction members at a different speed in the reverse direction, and means for effecting simultaneous rotation of said gear elements to drive said traction members at another feeding speed.

17. In a loading machine, a motor and feeding means operated by said motor including traction members, and operating and controlling means for said traction members including coaxial rotatable elements, planet mechanism cooperating with said elements and operatively connected to said traction members, gearing including gear elements operatively connected to said coaxial elements, means including brakes and clutches for holding two of said gear elements stationary during rotation of the third to effect driving of said traction members at one feeding speed, and means for holding said third gear element stationary during rotation of said first two to effect driving of said traction members at a different speed in the reverse direction and for effecting simultaneous rotation of said gear elements to effect driving of said traction members at another feeding speed.

18. In a loading machine, traction members, planet mechanism operatively connected to said traction members, and actuating means for said traction members comprising three shafts geared to said traction members through said planet mechanism, a motor,

operative driving connections between said motor and said three shafts including a clutch for each shaft for disconnecting the same at will, and means for holding two of said shafts stationary during rotation of the third to effect driving of said traction members to feed the machine in one direction, and for holding said third shaft stationary during rotation of said first two to effect driving of said traction members in the reverse direction.

In testimony whereof I affix my signature.
